DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

4 Sheets Drawing, 17 Pages Specification

The present invention relates to an automatic process for preventing a "natural selection" design automation computer program that is optimizing a specified objective function, for example, the location of a plurality of objects, from becoming permanently "stuck" at an unsatisfactory local minimum. The innovation presented in the disclosure is in the application of a novel "traffic-jam" routine which enables the optimization process to continue after it has reached such a local minimum. This routine operates most effectively in certain traffic-jam situations caused by unrecognized coalitions of objects where it is difficult to recognize the coalitions in question and difficult to maneuver them when unrecognized. Such coalitions can be broken up by an appropriate randomization of certain subsets of the total data, the subsets in question being demonstrably of high relevance to those unrecognized coalitions whose incorrect location has caused the unsatisfactory local minimum to be reached. The normal natural selection process may then continue to a more successful point even though the coalitions themselves remain unrecognized.

TRAFFIC-JAM
MECHANISM:

FIG. 1B

IS THIS THE BEST, LEGAL POSITION YET ACHIEVED ?

NO

YES

RESTORE THE BEST
LEGAL POSITION

EXAMINE A CROSSOVER NET:

HAS IT EITHER A FIXED ITEM,
OR 3 FREE ITEMS, ON THIS SIDE ?

NO

YES

EXAMINE EACH ITEM ON THIS SIDE TO WHICH NET REFERS:

DOES ITEM EXCEED SIZE CRITERIA; i.e., MORE THAN 8 TIES ?

YES

NO

PUT ITEM ON LIST FOR THIS SIDE

ANY MORE ITEMS ON THIS SIDE
WHICH ARE REFERENCED BY THIS NET ?

NO

YES

TRY OTHER SIDE OF SAME NET

BOTH SIDES TRIED

ANY MORE CROSSOVER NETS ?

NO

YES

PICK HALF THE ITEMS ON EACH LIST AT RANDOM

PUT PICKED ITEMS ON OPPOSITE SIDE

CALCULATE "SCORE" OF THIS ARRANGEMENT
